UNITED STATES PATENT OFFICE.

JOSEF HUTTER, OF NEW YORK, N. Y.

STARTING-LEVER.

1,167,562.

Specification of Letters Patent.

Patented Jan. 11, 1916.

Application filed May 21, 1915. Serial No. 29,470.

To all whom it may concern:

Be it known that I, JOSEF HUTTER, a subject of the Emperor of Austria-Hungary, and a resident of New York, in the county 5 of New York and State of New York, have invented certain new and useful Improvements in Starting-Levers, of which the following is a specification.

This invention relates to improvements 10 in devices for cranking or setting in operation any of the common forms of gas engines or other explosive motors and particularly to types used in propelling vehicles, boats and similar purposes.

15 The main object of the invention is to provide a manually operable crank for such purpose, that can be used with entire safety and freedom from danger to the operator should the shaft start to rotate suddenly in 20 the direction the crank is turned, or if the engine should accidentally back fire and rotate in a reverse direction.

Other objects are to provide such starters in forms readily applicable to existing conditions as well as original installations; that require no special experience in their use, and which are economical with respect to 25 wearing qualities and manufacturing cost.

These objects are attained by the novel 30 construction and combination of parts hereinafter described and shown in the accompanying drawings, forming part of this specification, and in which:

Figure 1 is a front elevation of a starter 35 made in accord with the invention. Fig. 2 is a side view of the same. Fig. 3 is an enlarged vertical sectional view, taken on line 3—3 of Fig. 1. Fig. 4 is a side elevation of the starter, looking oppositely from the 40 view shown in Fig. 2, and, Fig. 5 is a transverse sectional view taken on line 5—5 of Fig. 2.

In the drawings a support 10 is shown which may be part of the permanent structure 45 of the object to which the starter is applied. Through this extends the engine shaft 11, or its equivalent, to such distance as will allow ready accessibility. Rotatably surrounding the shaft is a sleeve 12, also 50 passing through the support 10 and having on it a fixed collar 13, limiting the longitudinal movement of the sleeve by contacting with the support 10 when the sleeve is moved outwardly. The inner end of the sleeve is 55 formed with ratchet teeth 14, preferably four in number, engageable with a pin 15

rigidly secured in the shaft 11 and extending outward on one or both sides of the shaft. In position to contact with the support 10, on its outer side, is a ratchet 16, 60 the same running loose on the sleeve 12; engaging with the teeth of the ratchet is a detent or pawl 17 pivoted to the support 10 and held in engagement by the spring 18.

A U shaped yoke lever having elements 19 and 20, connected by a bar 21, is mounted on the sleeve 12, the element 19 being rigidly secured to the side of the ratchet 16 by means of screws 22, and adjacent to the opposite face of the element 19 is a disk 23, 70 the same being keyed securely to the sleeve 12 upon which it is centered.

An operating lever 24, having a handle 25, is pivoted on the bolt 26 secured in the yoke lever elements 19 and 20. This operating 75 lever is provided with long hub 27 through which the bolt 26 passes; it has an extension 28 containing an elongated slot 29 through which the sleeve 12 passes, and a cam 30 in normal contact with the disk 23. A pin 31 is driven into the extension 28 and has bearing 80 against it the flat spring 32, the other end of which is rigidly secured to the edge of the element 20 in such manner as to keep the parts normally as shown in Figs. 1 and 5. 85 Another pin 33 is secured in the side of the disk 23, and extends outward into the recess 34, formed in the edge of the cam 30.

In operation the sleeve is pushed rearwardly on the shaft until the ratchet teeth 90 14 engage with the pin 15, whereupon the lever 24 is actuated in a clock-wise direction, causing the shaft to rotate until the motor starts to operate and throw the ratchet out of engagement by forcing the 95 sleeve to move forward or outwardly. This operation may require several revolutions of the starting lever and necessarily also of the yoke, causing the ratchet 16, to turn the detent, clicking over the teeth; when the motor is started both the lever and yoke may hang 100 pendent through gravity until again required. If however, the motor should back fire and start counter clock-wise, injury to the operator is certain to result unless provision is made; in order to avoid such mishap the ratchet 16 comes into use, for, as it cannot rotate backward, or the yoke which is connected with it, the result is that the starting lever is caused to pivot on the bolt 105 26, moving the extension 28 so as to cause the sleeve 12 to pass to the other end of the 110

slot 29, thereby freeing the pin 33 from the recess 34, in the cam 30, and allowing the pin to rotate around the cam, together with the keyed disk 28, without affecting the 5 operating lever.

From the foregoing it will be seen that an effective cranking lever is provided that may be used with the utmost safety to the operator, no matter how unskilled.

10 Having thus described my invention and ascertained its construction, purpose and use, what I claim as new and seek to secure by Letters Patent, is:—

1. In a safety starting mechanism, a shaft, 15 a sleeve movable thereon, and a support, of a yoke lever revoluble on said sleeve, a ratchet engaged therewith, an actuating lever pivoted in said yoke lever, a disk keyed to said sleeve, and means combined with the 20 disk and said actuating lever whereby the latter is prevented from turning when said shaft is rotated reversely from normal.

2. In a safety starting mechanism, the 25 combination with a rotatable shaft, a sleeve limitedly slidable and revoluble thereon, and means for operatively engaging said sleeve with said shaft, of an actuating lever oscillatable on said sleeve, a support for said actuating lever, said support being centered 30 on said sleeve, means for normally maintaining said lever in an operative position and means for disengaging said lever upon a reverse action of said shaft.

3. In a safety starting mechanism, the 35 combination with a shaft, a sleeve movable

thereon, and a fixed support, of a ratchet on said sleeve, a pawl engageable therewith, a forked lever on said sleeve rigid with said ratchet, an operating lever pivoted in said forked lever, an extension of said operating 40 lever having an elongated slot engaging said sleeve, a cam formed with said extension, a disk fixed to said sleeve, and a pin in said disk engageable with said cam whereby the disk may be moved together with said extension on said sleeve and also allow said shaft to rotate in a direction reverse to the normal.

4. In a safety starting mechanism, the 45 combination with a rotatable shaft, a fixed 50 support, a sleeve movable in said support on said shaft, and means for engaging said sleeve with said shaft, of a yoke lever revoluble on said sleeve, an actuating lever combined therewith, said actuating lever being 55 oscillatable with respect to said sleeve, means for preventing a reverse movement of said yoke lever, and means rigidly engaged with said sleeve for oscillating said actuating lever into an inoperative position, 60 said means becoming operative upon the reverse rotation of said shaft.

Signed at New York in the county of New York and State of New York this fifteenth day of May A. D. 1915.

JOSEF HUTTER.
